UNITED STATES PATENT OFFICE

2,230,721

ELECTRIC SWITCH

Donald G. Kimball, Stratford, Conn., assignor
to General Electric Company, a corporation of
New York

Application February 9, 1937, Serial No. 124,855

17 Claims. (Cl. 200—6)

My invention relates to electric switches and more particularly to electric switches of the multi-position tumbler type.

An object of my invention is to provide an electric switch of the multi-position, tumbler type in which it is impossible to move the switch from one operative position to another without stopping the switch in an intermediate position.

Another object of my invention is to provide an improved electric switch of simple construction which may be manufactured and assembled at a relatively low cost.

What I consider to be novel and my invention will be better understood by reference to the following specification and appended claims when considered in connection with the accompanying drawings in which Fig. 1 is a perspective view of the assembled switch; Fig. 2 is a side sectional view; Fig. 3 is a side view of the operating mechanism; Fig. 4 is an exploded perspective view of the operating mechanism; Fig. 5 is a side view of the switch with a push button control; Fig. 6 is an exploded view in perspective of the push button assembly; Fig. 7 is a sectional view of a modified form of switch; Fig. 8 is an exploded view in perspective of the switch of Fig. 7, and Fig. 9 is a top view of the switch of Fig. 7.

Referring to the drawings, Fig. 1, 10 indicates a base of insulating material to which is secured a plurality of stationary contacts two of which are indicated by the numerals 11 and 12. For cooperation with the stationary contacts 11 and 12 two movable contacts 13 and 14 are provided carried by springs 15 and 16 respectively. For moving the movable contacts 13 and 14 selectively into engagement with stationary contacts 11 and 12, cam 17 is provided. Cam 17 is secured to the end of shaft 18 as best indicated in Fig. 4. Shaft 18 is journaled in supporting structure 19. Supporting structure 19 is of U-shape having two upstanding arms 20 and 21. Between arms 20 and 21 a rocker 22 is provided and secured to shaft 18. Rocker 22 is also of U-shape and has two arms 23 and 24 in the top of which are located elongated slots 25 and 26 in which a roller 27 is adapted to be located. Roller 27 is held against the top of slots 25 and 26 by means of a coil spring 28 which is positioned by means of a retainer pin 29 provided with a tongue 30, slidably positioned in a slot 31 of shaft 18. The top of retainer pin 29 is seated in an annular recess 32 in the center of roller 27. Roller 27 is adapted to ride in tracks 33 and 34 provided in the arms 20 and 21 respectively of supporting structure

19. Tracks 33 and 34 are each provided with end notches 35 and 36 and a central notch 37. Located on the bottom of tracks 33 and 34 are projections 38. For movement of the roller 27 from one of the notches to another, an operating handle 39 is provided and journaled in the arms 20 and 21 by means of a pivot pin 40. Operating handle 39 is provided at its lower end with cam surfaces 41 which engage roller 27 adjacent its ends. When the switch is in its inoperative position as shown in Fig. 1, the roller 27 is located in the central notches 37 of tracks 33 and 34 and the operating handle 39 is in a vertical position. To engage the movable contact 14 with the stationary contact 12 the cam 17 must be rotated in a counterclockwise direction which is accomplished by moving the operating handle 39 to the right to the position indicated in Fig. 2. Upon the movement of the operating handle to the right, roller 27 is moved downwardly in slots 25 and 26 opposed by the coil spring 28 until it is out of engagement with the notches 37. Further movement of the operating handle to the right permits the roller 27 under the action of coil spring 28 to move to the left into notches 35. To return the switch from the operative position in Fig. 2 to the inoperative position in Fig. 1, the operating handle is moved to the left. The initial movement of operating handle 39, as best indicated in Fig. 3, by means of the cam surface 41 moves the roller 27 downwardly in slots 25 and 26 against the opposition of spring 28 until the roller engages the bottom of tracks 33 and 34. Further movement of operating handle 39 carries the roller 27 out of notch 35 along the bottom of tracks 33 and 34 until further movement of the roller 27 is prevented by projections 38 in the bottom of tracks 33 and 34. Operating handle or lever 39 must then be released and the roller moves into notch 37 under the action of coil spring 28. To move the switch to the operative position with movable contact 13 in engagement with stationary contact 11, the cam 17 must be rotated in a clockwise direction and the operating handle moved to the left. As the operating handle is moved to the left the roller 27 is moved out of notches 37 and into notches 36. By the provision of projection 38 in the bottom of track 34 it is impossible to move the switch from one operative position as from the position indicated in Fig. 2 to the other operative position without releasing the operating handle and permitting the switch to remain in the inoperative position for a sufficient period of time to again move the operating handle to

the other operating position. The elapse of time necessitated by the release of the operating handle and the temporary positioning of the switch in the inoperative position is enough to insure 5 that any arc drawn upon the separation of the contacts will be extinguished before another set of cooperating contacts are engaged. It has been found that when a circuit is broken which is supplied by alternating current if the arc is 10 extinguished at all, it will be extinguished within a few cycles of the alternating current voltage. In some switches it is possible to move the switch from one operative position to another within a period of time less than that necessary to 15 extinguish the arc drawn. When the switch in one position connects a conductor to one side of a three-wire 220 volt supply circuit and the other side of the conductor is connected to the neutral point the switching movement from one 20 operative position to another may impress on the 110 volt arc before it is extinguished a voltage of 220 volts. This frequently results in a disruptive arc which seriously damages the switch, if not completely destroying it. Thus, by 25 the provision of a stop assuring a sufficient lapse of time to permit the extinguishing of the arc drawn on the opening of an electric circuit the possibility of establishing a disruptive arc by moving the switch directly from one operative 30 position to another is prevented.

In Fig. 5, a modified form of switch is shown in which a push button control is substituted for the toggle operating handle of the switch of Fig. 1. A U-shaped operating lever 42 is provided pivoted 35 in the supporting structure 19 by means of a pivot pin 43. Operating lever 42 is provided with cam surfaces 44 corresponding to the cam surfaces 41 of operating handle 39. Push buttons 45 and 46 are loosely mounted on projections 47 and 48 respectively of operating lever 42. To secure the assembly together a retainer 49 is provided and secured in position by means of pivot pin 43 passing through openings 50 provided in the sides of retainer 49. The operation of the switch of Fig. 5 45 is identical to the operation of the switch illustrated in Fig. 1 except that the movement of the switch is initiated by pressure on either push button 45 or 46 depending upon whether it is desired to move the cam 17 in a counterclockwise or 50 clockwise direction.

In Figs. 7, 8 and 9 a modified form of switch is illustrated which is adapted particularly for use as a motor reversing switch. In a motor reversing switch it is particularly desirable to permit 55 the motor to slow down before it is energized to cause it to rotate in the opposite direction. Obviously, if the connections were changed instantaneously to reverse the motor before it had time to slow down at all, considerable strain would be 60 placed on the conductors, bearings, and other parts of the motor. By utilizing a switch that insures a delay in changing the connections to reverse the direction of rotation of the motor, a reduction of strain on the motor is accomplished 65 which may also prevent an early breakdown or failure of the motor. In Figs. 7, 8 and 9, the operating mechanism is the same as the operating mechanism illustrated in Figs. 3 and 4 and the same reference characters are used. In place 70 of the cam 17, as shown in Figs. 1, 2 and 5, for operating the movable contacts, the movable contacts 50 and 51 are secured directly to opposite ends of the shaft 18. Contacts 50 and 51 are insulated from shaft 18 by means of discs 52 and 53 respectively which are provided with shoulders

54 and 55 on which the contacts are mounted. For mounting the switch a supporting strap 56 is provided with threaded openings 57 and 58 adapted to receive screws for securing the switch in position. The stationary contacts 59 and 60 5 are mounted on two identical halves 61 and 62 forming a housing of insulating material. The two halves 61 and 62 of the housing are secured together by means of integral ears 63 and 64 which extend into slots 65 and 66 of supporting 10 strap 56 and integral ears 67 which extend from the bottoms of halves 61 and 62 and enter openings 68 in a bottom strap 69 which is secured to supporting structure 19 by means of screws 70. In the assembly of the switch the operating 15 mechanism is first assembled with the supporting strap 56 surrounding the supporting structure 19. The movable contacts 50 and 51 with the insulating discs 52 and 53 are mounted on the ends of shaft 18. The stationary contacts 59 and 60 are 20 mounted on the two halves 61 and 62. The two halves are then placed in position around the operating mechanism 19 with the ears 63 and 64 extending into slots 65 and 66 in the supporting strap 56. The movable contacts are prevented 25 from sliding off of the ends of the shaft 18 by means of projections 71 and 72 of the two halves 61 and 62, as best indicated in Fig. 7. The two halves 61 and 62 are then rigidly secured in position by means of strap 69 which is placed in position with the ears 67 located in the slots 68. To establish the circuit connections to cause the motor to rotate in one direction, the operating handle is moved to the left. If it is desired then to reverse the direction of rotation of the motor 30 the operating handle is moved to the right. As explained in connection with Figs. 1 to 4, the operating handle may not be moved all the way to the right without first stopping in a vertical position. In this position the circuit connections 40 are broken and so the motor begins to slow up before the switch can be operated to establish the circuit connections for the reverse rotation. If it were desired to use this switch to establish connections for rotating the motor at different 45 speeds any desired number of circuit connections could be accomplished simply by providing the desired number of notches in the track 34. Also, the direct changing of connections without a pause could be prevented by providing any number 50 of projections 38 in the proper locations.

From the foregoing it may be seen that a switch operating mechanism is provided which may be used for a multi position switch with means for preventing movement from one position to another without a pause in an intermediate position. Also, the switch is provided with a minimum number of simple parts which may be manufactured and assembled with facility and at a relatively 55 low cost. 60

What I claim as new and desire to secure by Letters Patent of the United States, is:

1. An electric switch comprising a stationary contact, a movable contact, a supporting structure, a shaft journalled in said supporting structure, means carried by said shaft for moving said movable contact into engagement with said stationary contact, a rocker connected to said shaft, a roller carried by said rocker and adapted to engage a track in said supporting structure, 65 a lever pivoted in said supporting structure and engaging said roller, and a projection in said track adapted to stop the roller in one position before movement to another position.

2. An electric switch comprising stationary 75

contacts, movable contacts, a supporting structure, a shaft journalled in said supporting structure, means carried by said shaft for selectively moving said movable contacts into engagement with said stationary contacts, a rocker connected to said shaft, a roller carried by said rocker and in engagement with a track in said supporting structure, a lever pivoted on said supporting structure and engaging said roller, and means to stop the movement of said roller along said track in one position.

3. An electric switch comprising stationary contacts, movable contacts, a supporting structure, a shaft journalled in said supporting structure, means carried by said shaft for selectively moving said movable contacts into engagement with said stationary contacts, a rocker connected to said shaft, a roller carried by said rocker in an elongated slot, a spring biasing said roller to the outer end of said slot, a track in said supporting structure having a plurality of notches and a projection, a lever pivoted in said supporting structure and having projections engaging said roller to move it along said track whereby the projection in said track prevents the movement of said roller from one notch to another without stopping in an intermediate notch.

4. An electric switch comprising stationary contacts, movable contacts, a supporting structure, a shaft journalled in said supporting structure, means carried by said shaft for moving said movable contacts selectively into engagement with said stationary contacts, a rocker connected to said shaft, a roller engaging said rocker and a lever pivoted on said supporting structure and adapted to move said roller along a track having a plurality of notches and a projection, whereby said rocker may be moved from one operative position to another and stopped in an intermediate position by the projection on said track.

5. An electric switch comprising a supporting structure, a shaft journalled in said supporting structure, movable contacts carried on said shaft, a rocker connected to said shaft, a notched track having a projection opposite one notch, a roller carried by said rocker and adapted to engage said track, a spring biasing said roller to one side of said track, a lever pivotally connected to said supporting structure and engaging said roller, a supporting strap engaging said supporting structure, a two-part housing of insulating material enclosing said switch and carrying stationary contacts positioned to be engaged by said movable contacts, and a bottom strap cooperating with said supporting strap to secure said two-part housing in position.

6. An electric switch comprising a two-part housing of insulating material, stationary contacts carried by said housing, movable contacts positioned to selectively engage said stationary contacts, an operating mechanism connected to said movable contacts and adapted to move said movable contacts from one operating position to another, a supporting strap connected to said operating mechanism, and a bottom strap connected to said operating mechanism, said supporting strap and said bottom strap having openings receiving integral ears from said housing to secure the two parts of said housing together.

7. An electric switch comprising a U-shaped supporting structure, a shaft journalled in said supporting structure, movable contacts carried by said shaft, a U-shaped rocker having elongated slots near the ends of the arms, notched tracks having a projection opposite one notch

provided in the two arms of said supporting structure, a roller carried in elongated slots of said rocker and engaging the tracks in the supporting structure, a spring biasing said roller to the top of the slots in said rocker, a lever pivoted in the arms of the U-shaped supporting structure and having cam shaped surfaces engaging said roller whereby movement of said switch is stopped at the notch with the projection opposite it upon movement from either side of said notch.

8. An electric switch comprising a supporting structure, a shaft journalled in said supporting structure, movable contacts carried by said shaft, a rocker connected to said shaft, a track provided in said supporting structure and having a plurality of notches on one side and a projection opposite one notch on the other side, a roller carried by said rocker and engaging said track, an operating handle pivotally secured to said supporting structure and having a cam shaped projection engaging said roller, said cam-shaped surface holding said roller against the side of the track opposite from said notch in movement from one position to another whereby said roller may not be moved past said projection without stopping in the notch opposite from said projection.

9. An electric switch comprising a supporting structure, a shaft journalled in said supporting structure, movable contacts carried by said shaft, a rocker connected to said shaft, a track provided in said supporting structure, a roller carried by said rocker and engaging said track, a lever pivoted in said supporting structure and having cam shaped surfaces engaging said roller, push buttons loosely fitting side projections of said lever, a retainer secured to said supporting structure and surrounding said push buttons whereby pressure on one of said push buttons will move said roller along said track from one operative position to another.

10. In an electric switch, a switch element having a plurality of operative positions and an intermediate inoperative position, a plurality of fixed and movable contacts, means operated by said switch element for engaging a movable contact with a respective fixed contact when said element is moved to an operative position and for disengaging said contacts when said element is moved to said inoperative position, and means including a notched track to lock said switch element momentarily at said intermediate inoperative position to prevent said switch element from being moved from one of said operative positions to another without stopping at said intermediate position.

11. In an electric switch, fixed and movable contact means, a switch element having a plurality of positions of rest including an intermediate position, means interconnecting said switch element and said movable contact means for controlling a circuit through said contact means when said element is moved to any one of said positions of rest, and means independent of current flow in the switch and actuated in response to movement of said switch element positively to prevent said switch element from being moved from any one of said positions of rest to another without stopping at said intermediate position.

12. In an electric switch, fixed and movable switch contacts, means to move said movable contact into more than two positions of rest, handle means for operating the switch and

means actuated by movement of said handle including stationary and movable members cooperating to prevent said movable contact upon moving from any one position toward an adjacent position from moving through said adjacent position without remaining therein when said handle means is moved substantially in an effort to move said movable contact through said adjacent position without stopping, the cooperation of said stationary and movable members being independent of current flow in the switch.

13. In an electric switch, fixed and movable switch contacts, means to move said movable contact into more than two positions of rest, handle means for operating the switch, and means, including cooperating members at least one of which is movable and engageable by a part of said movable contact moving means, effective upon operation of the handle to halt said movable contact in a position of rest adjacent its starting position when said handle means is moved substantially in an effort to move said movable contacts from any one position of rest through a position adjacent the starting position without stopping therein, the operation of said cooperating members being independent of current flow in the switch.

14. In an electric switch, fixed and movable switch contacts, means to move said movable contacts into more than two positions of rest, handle means for operating the switch, and means including a member movable in response to movement of said handle means upon operation of the switch to halt said movable contact in the position of rest adjacent its starting position when said handle means is moved substantially in an effort to move said movable contact from any one position of rest through

a position adjacent the starting position without stopping therein.

15. In an electric switch, fixed and movable switch contacts, means to move said movable contact into more than two positions of rest, handle means for operating the switch, fixed stop means and means movable in response to movement of said handle means upon operation of the switch and cooperating with said stop means to halt said movable contact in the position of rest adjacent its starting position when said handle is moved in an effort to move said movable contact from any one of said positions of rest through said adjacent position without stopping. 5 10 15

16. In an electric switch, fixed and movable switch contacts, means to move said movable contact into more than two positions of rest, handle means for operating the switch, a projection, and means movable in response to actuation of said handle means upon operation of the switch and cooperating with said projection to halt said movable contact in a position of rest adjacent its starting position when said handle is moved in an effort to move said movable contact from any one of said positions of rest through said adjacent position without stopping. 20 25

17. In an electric switch, fixed and movable contacts, means to move said movable contact into more than two positions of rest, handle means for operating the switch, and means normally permitting movement of a portion of said movable-contact-moving means in a predetermined path and responsive to movement of the handle to restrict said path and halt said movable contact in a position of rest adjacent its starting position upon movement from any one of said positions of rest. 30 35

DONALD G. KIMBALL.
